[57] CLAIM

The ornamental design for a toy UFO, as shown and described.

DESCRIPTION

FIG. 1 is a top view of the toy UFO according to my new design;

FIG. 2 is a front view thereof;

FIG. 3 is a right side view thereof, the left side view being substantially identical;

FIG. 4 is a bottom view thereof;

FIG. 5 is a rear view thereof;

FIG. 6 is a cross-sectional view taken along the line 6—6, in FIG. 2;

FIG. 7 is a front view of a second embodiment of FIG. 1, the difference residing in the addition of a transparent surface in the top compartment; and,

FIG. 8 is a cross-sectional view taken in the direction of the arrows along line 8—8, of FIG. 7.

The figure shown in broken lines in FIGS. 7 and 8, and the bathing agent shown in broken lines in FIG. 8, are for illustrative purposes only and form no part of the claimed design.
